ELECTRIC IGNITION SYSTEM

Leonard Darke, Coventry, England, assignor to
 General Electric Company, a corporation of
 New York

Application November 18, 1939, Serial No. 305,123
 In Great Britain May 31, 1939

3 Claims. (Cl. 123—148)

This system relates to an electric ignition system for internal combustion engines and more particularly to an electric ignition system for starting the internal combustion engine.

5 Heretofore the starting ignition for an internal combustion engine having a magneto to provide the electric ignition thereto, generally has been obtained from an auxiliary hand-turned or motor-turned magneto or by a battery operated trembler coil. In such a system, a high voltage is induced in the secondary windings of the starting ignition coil and is impressed on a trailing electrode of a main magneto distributor brush holder. The current which passes through this 10 electrode is then distributed to the appropriate distributor electrode so as to provide a spark at the spark plug for starting purposes.

An object of my invention is to provide an 15 ignition system having an improved starting ignition arrangement for an internal combustion engine.

A further object of my invention is to provide an improved ignition system utilizing a pulsating direct current voltage on the primary winding of 20 a magneto to provide the starting ignition voltage for an internal combustion engine.

Further objects and advantages of my invention will become apparent from the following description referring to the accompanying drawings, 25 and the features of novelty which characterize my invention will be pointed out with particularity in the claims annexed to and forming a part of this specification.

In the drawing, Fig. 1 diagrammatically illustrates a conventional magneto ignition circuit provided with contacts to which my improved starting arrangement may be connected; Fig. 2 is the magneto shown in Fig. 1 provided with an embodiment of my improved starting system, and 30 Fig. 3 is a modification of the starting system shown in Fig. 2.

Referring to the drawing, in Fig. 1 I have illustrated diagrammatically a conventional magneto ignition system including a magneto 10 having a core member 11 with a primary winding 12 and a secondary winding 13 wound thereon. To provide the necessary cyclic interruption in the magneto primary circuit the primary winding 12 has shunted across it a breaker 14 and a capacitor 15. The secondary winding 13 is in circuit with a conventional distributor 16 and a space discharge device or spark plug 17. Only one spark plug is shown, but it is to be understood that there is one in circuit with each one of the distributor 20 segments. A rotatable member is arranged to

provide the field excitation for the magneto and includes permanent magnet pole pieces 18 which are magnetically connected with the primary and secondary windings through the core member 11. The rotatable member is connected to 5 the crankshaft of an internal combustion engine either directly or through suitable gears and upon rotation thereof a current is induced in the primary winding 12. Upon the interruption of the primary winding circuit the breaker 14 which is 10 operated by the crankshaft either directly or by means of suitable gears through a cam member 19, voltage will be induced in the secondary winding 13 at the time the rotating brush of the distributor 16 is opposite a proper segment. Any 15 dynamo-electric machine of the magneto type may be used which is designed to produce the desired voltage in the secondary ignition circuit for the particular engine with which it is to be used.

In a conventional magneto, therefore, a sufficient voltage will not be induced in its primary winding until its rotatable member is rotated at a speed faster than starting or cranking speed, since it is the rotation of the rotatable member which causes the flux linking the winding to vary 20 in magnitude so that a voltage is induced therein. Since this rotation is caused by the engine through its crankshaft, some auxiliary arrangement must be used to produce the starting ignition for the engine. I provide the desired ignition for starting by impressing a suitable voltage 25 of varying magnitude on the primary winding of the magneto and this causes a voltage to be induced in the secondary winding which causes a current to be conducted to the spark plug 30 through the distributor. In the circuit diagram shown in Fig. 1 the source of this voltage may be connected across the terminals 20 and 21.

In Fig. 2 I have shown a simple and effective means for producing a voltage of varying magnitude and the energy source of this voltage includes a battery 22 across which is connected a trembler device having a trembler coil 23 which actuates an interrupter having contacts 24 and 25. In this circuit interrupter the contact 25 is 40 carried by an armature 26 which is adapted to cooperate with a core member 27 of the trembler coil and the contact 24 is held stationary. In order to cause a current from the battery to flow through the trembler device a switch 28 which is 45 in circuit therewith is closed. This flow of current will set up a magnetic field which attracts the armature and opens the contacts. A suitable capacitor 29 may be placed across these contacts 50 so as to minimize arcing. When the contacts 55

open the direct current stops flowing in the trembler coil and the magnetic field begins to subside. Since the armature is biased towards the contact 24, the contacts will close and direct current will again flow through the trembler coil. This opening and closing of the contacts will continue and a pulsating voltage will therefore appear across the interrupter contacts. In order to prevent a heavy current discharge through the primary winding and short circuiting of the battery, the contacts 24 and 25 are connected across the primary winding through two condensers 30 and 31. These connections are made through wires 32 and 33 and the capacitors 30 and 31 are respectively connected in series with these wires. One side of the primary winding may be grounded so as to form a return path from the spark plug. The side of the battery which is connected to one side of the trembler coil may also be grounded. Since a pulsating voltage appears across the interrupter contacts the condensers 30 and 31 will be charged and discharged and a pulsating current will flow through the primary winding. Thus the pulsating current flowing through the primary winding will induce an alternating voltage in the secondary winding which will cause a current to flow through the distributor to a spark plug. A spark is only desired when the magneto breaker contacts are open so that ignition will occur at the proper time. Since these contacts, when closed, form a much lower impedance path to the current than the primary winding, the pulsating current will flow in the primary winding only when the contacts are open, thus providing a spark at only the proper time.

In the modification shown in Fig. 3, a circuit is shown similar to that illustrated in Fig. 2, except that the battery is not grounded and the condenser 31 is omitted. This circuit may be used when grounding of the battery is not desired. It is, of course, to be understood that condenser 30 may be omitted instead of omitting 31. The starting circuit, however, will operate similarly to that described in relation to Fig. 2. Thus I provide a new and improved ignition system for supplying starting ignition voltage for an internal combustion engine which makes use of a conventional magneto which thereafter provides the ignition after the engine has been started.

Modifications of the particular arrangements which I have disclosed will occur to those skilled in the art, so that I do not desire my invention to be limited to the particular arrangements set forth and I intend in the appended claims to cover all modifications which do not depart from the spirit and scope of my invention.

What I claim as new and desire to secure by Letters Patent of the United States is:

1. An ignition system for an internal combustion engine including a magneto having a primary and a secondary winding and an excitation means responsive to the operating speed of said engine for inducing a current in said primary winding, said primary winding having one side thereof

connected to ground, a circuit breaker having an electrical connection with said primary winding, means arranged to actuate said circuit breaker periodically responsive to the operating speed of said engine for inducing a voltage in said secondary winding, a battery, an interrupter, and a coil for actuating said interrupter, connections including said coil for connecting said interrupter across said battery, and connections between said interrupter and said primary winding for connecting said interrupter across said primary winding, said connections between said interrupter and each side of said primary winding being provided with a capacitor, said interrupter being so constructed and arranged as to be periodically actuated by said coil so that ignition is provided for the engine during starting.

2. An ignition system for an internal combustion engine including a magneto having a primary and a secondary winding and an excitation means responsive to the operating speed of said engine for inducing a current in said primary winding, said primary winding having one side thereof connected to ground, a circuit breaker having an electrical connection with said primary winding, means arranged to actuate said circuit breaker periodically responsive to the operating speed of said engine for inducing a voltage in said secondary winding, a battery, an interrupter, and a coil for actuating said interrupter, connections including said coil for connecting said interrupter across said battery, and connections between said interrupter and said primary winding for connecting said interrupter across said primary winding, said connection between said interrupter and one side of the primary winding being provided with a capacitor, said interrupter being so constructed and arranged as to be periodically actuated by said coil so that ignition is provided for the engine during starting.

3. An ignition system for an internal combustion engine including a magneto having a primary and a secondary winding and an excitation means responsive to the operating speed of said engine for inducing a current in said primary winding, said primary winding having one side thereof connected to ground, a circuit breaker having an electrical connection with said primary winding, means arranged to actuate said circuit breaker periodically responsive to the operating speed of said engine for inducing a voltage in said secondary winding, a battery, an interrupter, and a coil for actuating said interrupter, connections including said coil for connecting said interrupter across said battery, and connections between said interrupter and said primary winding for connecting said interrupter across said primary winding, said connection between said interrupter and the ungrounded side of the primary winding being provided with a capacitor, said interrupter being so constructed and arranged as to be periodically actuated by said coil so that ignition is provided for the engine during starting.
